The ornamental design for a bottle with structural columns, as shown and described.

DESCRIPTION

FIG. 1 is a perspective view of a front side and right side of the bottle according to our new design;

FIG. 2 is a perspective view of the rear of the bottle; and,
FIG. 3 is a perspective view of a front side and left side thereof.

The broken lines showing portions of the bottle with structural columns are included for the purpose of illustrating portions of the article and form no part of the claimed design.
